UNITED STATES PATENT OFFICE.

EDGAR F. HATHAWAY, OF DORCHESTER, AND CHARLES LEA, OF BOSTON, MASSACHUSETTS, ASSIGNEES TO AMERICAN WARP-DRAWING MACHINE COMPANY, A CORPORATION OF MAINE.

MACHINE FOR HANDLING TUFT-YARNS FOR CARPET-LOOMS.

1,153,864.

Specification of Letters Patent.

Patented Sept. 14, 1915.

Application filed February 18, 1909. Serial No. 478,683.

To all whom it may concern:

Be it known that we, EDGAR F. HATHAWAY and CHARLES LEA, both citizens of the United States, and residing, respectively, at Dorchester and Boston, both in the county of Suffolk and State of Massachusetts, have invented an Improvement in Machines for Handling Tuft-Yarns for Carpet-Looms, (Case C,) of which the following description, in connection with the accompanying drawings, is a specification, like letters on the drawings representing like parts.

Our invention relates to the manufacture of carpets or rugs of the Axminster and similar types, being more particularly concerned with the provision of improved means for placing the tuft yarns, customarily used in the weaving of such carpets or rugs, in the separate tubes of a tube frame 20 of the type ordinarily employed with carpet-loomis of this class.

Our invention will be best understood by reference to the following description when taken in connection with the accompanying illustration of one specific embodiment thereof, while its scope will be more particularly pointed out in the appended claims.

In the drawings; Figure 1 is a plan view of a machine for tubing the tuft yarns, such machine embodying one form of our invention, the same being shown broken away so that a larger scale may be employed; Fig. 2 is a similar view of the same machine shown in front elevation; Fig. 3 is a side elevation, on an enlarged scale, in section taken on the line 3—3 in Fig. 1 and looking in the direction of the arrow; Fig. 4 is a sectional elevation showing in detail the operating handle and connected gearing; Fig. 5 is a detail in end elevation showing the connection of the transfer comb to the ends of the spool; Fig. 6 is a sectional view similar to Fig. 2, but showing the needles and cooperating parts in a different position. Fig. 7 is a front elevation, partly broken away, showing one end of the machine on the scale of Fig. 2, but showing the transfer comb shifted laterally; Fig. 8 is a detail in perspective showing the relation of the tubes and needles to their respective guiding devices; Fig. 9 is a sectional elevation showing a portion of the machine on an enlarged scale, such section being taken on

the line 9—9 in Fig. 2 in the direction of the arrow; Fig. 10 is a sectional detail of the sliding support for the vertically fixed knife of the shearing mechanism; Fig. 11 is a view in perspective of one end of the transfer comb; Fig. 12 is a detail in perspective of the locking bar for the spool holder; Fig. 13 is a plan of a portion of the spooling machine showing the attachment thereto for receiving the transfer comb; Fig. 14 shows in perspective a portion of the holder for the transfer comb; Fig. 15 is a side elevation showing the relation of the vertically movable comb holder to the spooling machine; Fig. 16 is a sectional elevation showing the comb and holder elevated; and Fig. 17 is a view in perspective of the transfer comb with its cap or retainer applied.

Referring to the drawings and to the particular embodiment of our invention there shown, we have therein illustrated in Figs. 1 to 12 inclusive a machine wherein the spool, carrying the tuft yarns wound thereon, may be placed and held in such relation to the tubes of a tube frame that, by a single operation, the entire series of tuft 80 yarns may be placed or inserted with great certainty and accuracy through the tubes by suitable yarn-placing means, herein a series of needles, one for each tube.

Referring first to the preparation of the tuft yarns prior to installation in the tubing machine, we have shown in Figs. 13 to 17 inclusive means whereby the tuft yarns, after being wound upon the spool in the spooling machine, may be held separated, 90 and maintained in such separated condition while placed in the tubing machine so that they may be drawn accurately through the tubes of the tube frame.

Referring to Figs. 13 to 17 inclusive we have there shown a separating device comprising a transfer comb 1, preferably formed of sheet metal, and presenting a series of upright teeth 2 formed with preferably well rounded or beveled tips. This 100 comb is so placed in the spooling machine beneath the tuft yarns that, after the spooling operation is completed, it may be raised to receive the tuft yarns 3 between the teeth 2, as represented in Fig. 14.

For the sake of illustration an ordinary

form of spooling machine 4 is represented in Figs. 13 and 15, the same being provided with well-known mechanism for receiving the spool 5 and winding the tuft yarns about the same. During such operation the yarns 5 unwind from bobbins (not shown), the usual reed or separator 6 being provided which presents upright pegs or their equivalents 7 for separating and keeping separated 10 the individual yarn strands or groups of strands as they pass to the spool. The comb is supported with its teeth in upright position by a suitable holder 8 immediately beneath the tuft yarns as the latter pass from 15 the reed to the spool, so that, when the comb is elevated (Fig. 16) the teeth are caused to pass between the sets of strands, as shown in Fig. 14.

When constructed of sheet metal the lower 20 edge of comb is preferably turned or curled over on itself, as shown, and is adapted to rest in a groove or pocket in the holder 8. This consists of a cross-bar extending between the upright end supports 9, which 25 latter are slidably mounted in brackets 10 secured to the frame of the spooling machine. For raising and lowering the reed the end supports are each provided with rack teeth 11 which mesh with the pinions 30 12, the latter being fixed to the shaft 13 extending transversely the machine beneath the reed 6, each end of the shaft being provided with a handle 14 whereby it may be turned and the comb raised or lowered at 35 will.

The comb, when inserted in the holder, fits between two transverse pins 15, so that the teeth of the comb are caused positively to align with the pegs in the reed and to 40 pass with certainty between adjacent yarn strands or sets of strands when the comb is raised.

After the spooling operation, the comb, which has previously been inserted in the 45 depressed holder 8 and is then positioned as shown in Fig. 15, is elevated to the position shown in Fig. 6 by turning the handle 14, each set of strands entering a separate space between the teeth of the comb. Suitable 50 means for maintaining the holder elevated are preferably provided, such for example, as the pin 16 fixed to the lower end of the supporting rod 9 and adapted to be yieldably clasped and held by the stationary 55 spring clip 17 when the holder and comb are elevated.

With the holder elevated, the yarns are prevented from slipping out of the comb by the application thereto of a cap piece or retainer 18, which latter preferably consists of a bent or turned over metallic strip adapted to slip over the points of teeth (as shown in Fig. 17) and close the mouths of the slits 60 against the exit of the yarn strands, preferably, however, without clamping or grip-

ping the yarns or otherwise preventing their free longitudinal draft between the teeth.

The cap may be retained on the comb in any suitable manner as, for example, by means of a resilient finger piece 19 (one of which is shown in Figs. 11 and 14) riveted or otherwise secured, one at each end of the comb, and having a hooked end which overlies and holds the comb against displacement (see Fig. 11). The locking finger is sufficiently resilient to permit its being bent back to allow either the application *or* withdrawal of the retaining cap piece.

With the retaining cap in position the comb may then be attached to the spool by suitable means so that, no matter how much the spool may be handled in transference or how long afterward the tubing operation may be performed, the comb cannot be accidentally displaced. In the described embodiment of our invention (Fig. 11) we have shown the comb provided at each end with an attachment member, herein in the form of a spring 20. The latter has an eye 21 which (see Fig. 5) may be slipped over the small pintle 22 at the end of the spool 5 and employed to attach the comb to the spool, the former having first been laid flatwise against the wound-on yarn. The wound-on 45 yarn strands can then be severed, leaving them in the condition represented in Fig. 5 and the spooling operation can thereafter proceed in the usual manner, and the operation repeated as to another spool as above described.

The attaching springs 20 are preferably each provided with means, such as the angular clip 23 whereby the operative can readily apply the spring eye 21 to the pintle or release the same therefrom. It will be seen that this provides a means for permanently holding the comb in definite relation to the spool and the wound-on yarn strands until required for the tubing operation without the necessity, however, of clamping the yarns in the comb. The comb (see Fig. 5) being drawn flatwise against the wound on yarn acts also as a clamp preventing the unwinding of the yarn from the spool. In this condition each spool is ready 115 for the tubing operation, but may be laid aside for an indefinite period before such operation without impairing in any way its adaptability therefor.

Referring now to the tubing or threading 120 machine (see Figs. 1 and 2), the latter comprises end frame members 24 between which, near the front of the machine, there extends a bed piece or plate 25 (Fig. 3). The bed plate serves as a support or rest for the tube frame (see Fig. 9), which latter is inserted in the machine with the tubes 26 resting on the bed plate and their small ends pointing inwardly, the tube connecting bar 27 resting against the front edge of the bed plate. 130

Preferably two or more brackets or hangers 28 are provided having bent ends overlying the front of the tube-connecting bar 27, these acting to position the tube frame and also to hold flat against the tube bar the spring clips 29 which are fastened thereto, the said spring clips being utilized, when the tube frame is applied to the spool, to frictionally engage with the spool ends and hold the tube frame in fixed position thereon.

Preferably means are provided which tend to align, and hold aligned, with the needles the individual tubes, such means herein being embodied in the form of a swinging clamp bar 30 (Fig. 9), which latter is pivoted in upright brackets 31 mounted upon the end of the bed plate 25 and provided at one end with the hand lever 32, so that it can be swung into or out of engagement with the tubes. The clamp bar along its active edge is provided with teeth or serrations 33 (see Figs. 8 and 9) which are adapted to enter and fit the spaces or depression between adjacent tubes, so that, when the clamp bar 25 is swung over from the dotted line position shown in Fig. 9 to the full line position there shown, the teeth enter between the tubes and clamp the tube frame in alignment with the needles. The rear corners of the teeth, or those which first engage the tubes, are preferably beveled or otherwise shaped so that they act as wedges and, entering between the tubes, wedge the tube frame laterally into the required alignment with the needles if the former happens to be slightly offset to one side or the other of the required position. By this means the tube frame is not only held clamped, but is automatically brought with certainty into the required alignment.

Referring now to the means for installing and holding the spool and the wound-on yarn strands in the machine, the latter is provided with holders or boxes 34 depending from the bed plate, in which holders the ends or heads of the spool are placed. After the spool is inserted it is locked at each holder against turning in the holder or withdrawal therefrom by means of a locking dog or shoe 35 pivoted thereon. To control the locking dogs simultaneously for the locking or release of the spool, each dog is provided with a pin 36 which projects up through a slot 37 (see Fig. 12) in the transverse locking bar 38. The bar extends across the machine terminating in a portion 39, bent as shown in Fig. 2 or otherwise suitably formed, to permit the operator to grasp and move the same. The holding brackets or hangers 34 are transversely slotted to slidably support the bar, the latter being held in such slots by the angle clips 40.

The slots 37 in the locking bar which receive the pins on the locking dogs are so inclined that, as the bar is slid transversely

the machine, the locking dogs are swung up or down, the latter position being represented in Fig. 9. When swung up, the dogs permit the introduction or withdrawal of the spool heads from the holders, but when 70 swung down, assume the position shown in Fig. 9 where they reach out along the edges thereof to a sufficient extent to retain the spool in the holder. As shown in Fig. 9 the contacting edges of the dogs are provided 75 with teeth 41 which are adapted to grip the wooden edges of the spool head, there being provided a spring 42 in each holder which tends to throw the spool out against the dog. The teeth are so shaped that they 80 oppose the unwinding movement of the spool, although for purposes of adjusting the yarn strands when installing them in the machine they can always be unwound from the spool without unlocking the dogs by 85 pressing the spool in the holder and against the spring 42 which frees the heads from the teeth of the dogs. While the operator can thus readily free the spool to unwind it or can turn the spool while locked in the holder 90 to wind up the yarn, it will be observed that it is securely locked against turning due to any pull received along the line of draft of the free ends of the yarn, after the latter has 95 been led upwardly into the machine.

Having locked the spool in the holder the operator disconnects the comb from the spool, and after pressing back the spool in the holder to release it and unwind a sufficient length of yarn, he places the comb in a grooved comb holder 43 located in front of and at a level just above, the tube frame, the yarn strands therefor assuming the position shown by dotted lines in Fig. 9.

Referring now more particularly to Figs. 1, 3 and 6, the needles 44, of which there is one for each tube, are carried upon a suitable cross-head or holder 45 at the rear of the machine and are so arranged that, at the proper time, they may be projected forwardly each through one of the tubes to seize a yarn strand or strands and draw the same through its tube from the larger to the smaller end thereof. The needle cross-head 45, as shown in Figs. 1 and 3, is fixedly secured at each end to a slide bar 46, the latter adapted to slide through bearings or guideways, one of which, 47, is supported at the rear of the frame piece 24 and the other of which, 48, is suspended from the bed plate 25.

To advance or retract the needles, the lower edge of each slide bar 46 is provided with rack teeth 49 which mesh with gears 50, the latter secured to the main operating shaft 51. The shaft 51 is turned (see Figs. 1, 2, 3 and 4) by means of pinions 52 secured one at each end thereof and meshing with a gear segment 53, the latter carried back by a lever arm 54 pivoted at 55 to the 130

frame. The two levers 54 at opposite sides of the machine are connected by the transverse rod 56, which the operator, while standing in front of the machine, can raise or lower at will to advance or retract the needles.

In Fig. 3 the needles are shown in their rearward position and in Figs. 6 and 8 in their advanced position, wherein their hooked ends have been projected through the tubes and beyond the line of the yarn strands. With the needles in this position, the yarn strands are then given a slight lateral movement to lay the yarn across the needles and within the path of the needle hooks to be seized by the latter on their return. In the present embodiment of our invention this is accomplished by shifting the transfer comb itself, this acting, because of the close relation which the transfer comb bears to the needles and tubes to lay the yarn strands with certainty across the needles and within the hooked portions thereof, as represented in Fig. 7. Preferably the shifting operation is performed mechanically and immediately following and consequent upon the assumption by the needles of their extreme advanced position, as shown in Fig. 6. To this end the holder 43 of the transfer comb is provided at opposite ends with slotted extension portions 57 and 58, which are slidably supported between ears formed by projections of the supporting brackets 31. The bracket ears are provided with fixed pins 59 which engage the slots in the holder and permit a limited sliding movement of the latter with its attached comb. The projecting end of the holder portion 57 (Figs. 1, 2 and 7) is provided with an upright lug 60 which is secured thereto by means of a stud 61 passing through a slot 62 in the holder so as to permit slight longitudinal adjustment of the lug thereon. The lug is provided with a rearwardly projecting pin 63 which is engaged by the forked end of the upright arm 64 of a bell-crank lever which is pivoted upon the stud 65 secured to the bed plate 25.

The other arm 66 of the bell-crank carries a small roll 67 which is normally pressed inward against the slide bar 46 through the medium of a spring 68 encircling the stud 65 and having one end secured to the lever arm 64 and the other to the stud. When thus positioned, with the roll bearing against the slide bar the comb is held as represented in Fig. 2 maintaining the yarn strands in vertical lines. Immediately back of the roll the slide bar is provided with a cam member 69 having preferably a conical or wedge-shaped nose succeeded by a circumferentially grooved portion so shaped as to form a seat for the roll. The cam member is loosely mounted on the slide bar so that, on advancement of the needles, it remains fixed

relatively to the roll until the needles approach their extreme forward position. The cam member then becomes engaged by a pin 70, or other suitable abutment, fixed on the slide member and this causes the advancement of the latter from the position shown in Fig. 3 to the position shown in Fig. 6. The advance of the cam lifts the roll upon its conical nose and leaves it seated in the groove 69. Such movement swings the bell-crank about its pivot shifting the holder and the comb from the position shown in Fig. 3 to that shown in Fig. 7.

The needles having been projected through the tubes and beyond the yarn strands by movement of the operating bar 56 to the extreme upper position, the operator then swings the bar down, causing the needles each to retract and seize the yarn or yarns laid across its shank and draw them through the appropriate tube. The return shifting movement of the comb, however, is preferably delayed until the needle hooks have drawn the yarns into the tubes, such return movement herein not taking place until the close of the needle return movement. Herein in the return of the comb and its holder to its initial position is effected by means of the abutment 71, shown in the form of a washer secured to the forward end of the slide bar 46, which abutment engages the cam 69 and draws it back to its initial position, thereby releasing the roll and the bell-crank, the pressure of the roll against the cam having acted meanwhile to hold the cam fixed notwithstanding the movement of the slide rod.

In the practical employment of these machines it is preferable that the needles not only be guided close to the tubes prior to entering the same, but that their hooked ends be rigidly spaced when out of use and retracted. Furthermore it is also desirable to provide guidance for the ends of the needles projecting through the tubes and before seizure of the yarn, otherwise the tubes which through misuse are apt to become bent and out of alignment, are likely to throw some of the needles to one side or the other of the desired position.

Herein we have provided guidance for the needles close to the mouths of the tubes where they enter, the guiding means being capable of retraction with the needles to permit the introduction of suitable yarn shearing or trimming devices between the tubes and the needles, and such guiding means herein also holds in rigid separation the hooked ends of the needles when retracted. To this end there is provided a transverse guide bar 72 which is slotted to receive each needle and hold it in separated relation to the adjacent needles, as represented in Fig. 1. Such guide bar is secured at its ends to supporting rods 73, the latter slidably

130

mounted in the cross-bar or holder 45. Each rod 73 is yieldably connected to the cross-bar by means of a spring 74 (see Fig. 3) and is thereby drawn forward to bring the guide bar close to the needle points when the latter are retracted. The forward movement of the bar is limited by means of a pin 75 in each rod, which pin abuts against the cross-bar or holder.

10 When the needles are advanced the guide bar 72 is advanced with them until the needle hooks are close to the mouths of the tubes when the guide bar is brought to rest by abutting against a fixed part of the machine, herein the vertically fixed knife 76 of the shearing mechanism to be later described (see Fig. 6). The needles continue their advance through the tubes, merely stretching the connecting springs 74, the guide bar being subsequently returned with the needles to the position shown in Fig. 3 after the latter emerge from the tubes with the engaged yarn strands.

15 The needles are secured to the cross-bar between suitable spacing members by means of a key rod 77 of circular cross-section seated half in each needle and half in a plate 78 bolted to the top of the cross-bar. To provide guidance for the needles on the opposite side of the tubes, means are provided whereby the needles, as they emerge from the tubes and before engaging the tuft yarns, are directed into the proper course. Any suitable means may be employed for 20 this purpose and, if desired, such guiding means may be carried and presented by the swinging clamp bar 30, but herein there is provided an additional member comprising a needle guide bar 79 extending across the machine and adapted to be swung down directly back of the large ends of the tubes and in the path of the needles as they emerge therefrom. Such needle guide (Figs. 2, 8 and 9) is carried at each end upon arms 80 25 pivoted in the brackets 31, near the end of the bed plate 25, and is provided at one end with a depending lever arm 82 by means of which the guide bar can be swung from the full line position shown in Fig. 9 to the dotted line or active position.

30 The edge of the needle guide is provided with teeth 83 (Fig. 8) which are adapted to swing down in between the needles and, as the latter emerge from the tubes, wedge such as are out of alignment into the required alignment. Herein the needle guide is depressed by mechanical means and properly timed with relation to the needle advance. For this purpose the arm 82, normally 35 drawn back by the spring 84, which has its opposite end secured to the bed plate to hold the needle guide up, is thrown forward to swing the needle guide down, as described, by means of a pin 85, or other suitable part; 40 fixedly secured to the slide rod 46. This

pin engages the lever arm 82 and swings the needle guide down. This preferably takes place just as the needles emerge from the tubes, and the lever is provided with an inclined end which rides up on the pin as 45 the needles continue to advance, so that the needle guide, when swung down, is held there until the needles have seized the yarn strands and drawn them back into the tubes, whereupon, the pin 85 moves back and allows the lever 82 to drop. The lever arm is shown as engaged by the pin 85 in the dotted line position shown in Fig. 9.

50 Prior to use in the loom it is necessary to cut the drawn-in yarn strands evenly at a fixed predetermined distance from the ends of the tubes. Herein we have provided shearing means whereby this is automatically accomplished in the same operation with the tubing of the yarns. To this end 55 there is provided the vertically fixed knife 76, already referred to which, however, is supported at the rear edge of the bed plate so as to be capable of a slight yielding movement toward the plate. To secure this, the 60 knife is supported on studs 86 (Fig. 10) each slidably mounted in a pocket in the bed plate and provided with an upright pin 87 working in a small transverse slot 88 in the plate. Relatively stiff springs 89 are seated 65 at intervals in the bed plate and bear against the knife to force the latter back and the pins 87 to the rearward limit of the slots 88.

70 The threads of the yarn strands when drawn back by the needles, lie directly over the upper edge of the knife 76 and in that position are cut off by a downward movement of the vertically movable knife 90. The latter has an inclined edge, as shown in dotted outline in Fig. 2 and at its extreme 75 left hand end, as viewed in Fig. 2, which end, when depressed, first meets the fixed knife blade, it is connected to a cam member 90* having a lower beveled edge as shown at 91 in Fig. 6. The blades are so arranged 80 that the vertically movable blade 90, when elevated, lies somewhat over the stationary fixed blade, and when depressed, acts first through the cam member 90* and subsequently through the blade member 90 itself 85 to wedge the blade 76 forward against the yielding springs 89. Thus, as each succeeding portion of the blade edges cross, the shearing action is accomplished by a pressing back of the stationary fixed blade, thus 90 giving in effect the action of a pair of shears and imparting a clean shearing cut to the 95 yarn.

100 To impart suitable and appropriately timed movement to the vertical movable blade, the latter is bolted to the transverse supporting beam 92 which, in turn, is fixedly secured at each end to vertically reciprocable plunger rods 93, the latter guided for 105 sliding movement in upper and lower 110

brackets 94 and 95 attached at the frame member 24. One side of each plunger rod 93 is toothed to form a rack 96, and this engages in each case with a pinion 97, the latter secured to the shaft 51 which carries the main driving gear 52 and the needle operating gear 50. The parts are so geared that, as the needles are retracted out of the path of the shearing mechanism, the latter descends from the position shown in Fig. 6 to that shown in Figs. 3 and 9, and trims the ends of the drawn yarns. On the other hand, when the needles are advanced, the upper blade member is lifted up and out of their path.

In practice it is quite necessary that the projecting ends of the drawn-in yarns should be trimmed evenly and with certainty to the required distance from the ends of the tubes. In order that the tube frame, when withdrawn from the machine, may have the yarn strands cut the required length and may also be held fixed in this relation on the spool, thus being ready for the loom without the need of any further step or operation, means are preferably provided so that, after shearing, and preferably when sheared the ends of the yarn strands are held clamped and the tube frame is also held clamped. This permits the operator to remove the spool from its holder, wind up the slack yarn thereon and apply the spool to the tube frame by inserting pins 22 thereof in the end springs 98. The latter are customarily provided on the tube frame and, when the latter is installed in the machine, project outwardly from the machine as shown in Figs. 3 and 6. The spool then occupies the position shown in dotted lines in Fig. 9 and the tube frame, spool and yarn ends being definitely and fixedly positioned each relatively to the other; the tube frame and yarn ends may be released and withdrawn from the machine for use in the loom without further attention. To this end we have provided clamping or holding means for clamping the yarn strands between the small ends of the tubes and the knife. Such clamping means may be embodied in various forms, but herein we have provided a holding bar 99 extending across the machine and carried by the shearing mechanism so that, when the needles are advanced, such bar is elevated with the knife 90, out of the way, as shown in Fig. 6. When the needles are retracted, however, and the shearing blade descends, the holding bar is brought down across the drawn-in yarn ends clamping them tight against the flat top of the bed plate 25, as shown in Fig. 9.

Preferably, though not necessarily, the holding bar engages with the yarns just prior to the shearing operation so that, before being cut, the yarns are gripped tight over the bed plate and relatively near the

knife, their displacement from the taut drawn-in position being thereby prevented, and the accuracy with which the yarn is trimmed down relatively to the ends of the tubes being increased.

Referring to the constructional details of the holding bar, the latter is fixedly secured, to the slotted lower ends of two or more vertical plunger pins 100. Each of the latter is provided with a coil spring 102 compressed between supporting arms 101 on the overhead beam member 92 and the bar, and acting to depress the holding bar to its lowermost position (Fig. 6). Its downward movement is limited by an abutment, such as the collar 103 carried by each pin, which abutment contacts with the upper side of the beam supporting arm 101. On the depression of the shearing blade the holder bar clamps the drawn-in yarns just prior to the shearing cut, subsequent depression of the blade resulting merely in compressing more or less the restoring springs 102. The holder bar may be of any suitable material and of any desired shape but herein is formed of a metal strip or plate with a lower rounded or beveled edge.

In order that the yarns may be released from the holder bar for the withdrawal of the spool and tube frame from the machine, as described, while still leaving the needles retracted and the shearing blade depressed (in which position it will be noted the parts are ready for the drawing-in of the next set of yarns subsequently to be presented to the machine), means are provided for independently lifting the holder bar and releasing the yarns without moving the main operating mechanism or lifting the shearing blade. Herein such release is effected simultaneously with the releasing movement of the tube clamp 30. For this purpose each collar 103 on the plunger pins 100 is provided with a forwardly directed finger 104 which (see Fig. 9) overlies the clamp bar 30 so that, when the latter is swung up by its handle 32, the bar engages the two fingers 104 and lifts the holder bar 99 against the compression springs 102 so that the yarn ends are free to be withdrawn from the machine with the spool and tube frame. The elevated position of the holder bar and fingers will be clear from the dotted line shown in Fig. 9. The operator, therefore, having drawn in and trimmed the yarn strands, releases the spool by movement of the releasing bar 43, winds up the slack on the spool and fastens the latter to the tube frame springs 98, as described, the yarns meanwhile being held fixed by the holding bar, so that no displacement can take place. Movement of the handle 32 thereupon serves to release both the tube frame and the yarns for withdrawal from the machine.

The comb 1, when it is inserted in the tub-

ing machine with the connected yarn strands, brings the latter into a definite relation with reference to the path of the needles thereon through the provision of positioning means in the comb holder. Such positioning means are provided in the form of positioning pins 105 in such holder (see Fig. 2) between which the ends of the comb must be inserted. The tube frame is also approximately positioned with reference to the needle path by means of the upright positioning pin 106 shown at the left-hand end of the bed plate, as viewed in Fig. 2. A corresponding pin might be employed for the opposite end of the tube frame, but preferably one end only is positioned so that the operator will place the tube frame in the machine with reference to the pin 106, allowing the alinement clamp 30, when subsequently applied, to enforce, if needed, a definite alinement with the needles.

It will thus be seen that the yarn transfer comb is definitely and predeterminedly related first to the reed pins in the winding machine and later to the needles and tubes in the tubing machine so that the yarns are received from the bobbins, then transferred and later presented to the needles for the tubing operation by the same instrumentality, *i. e.* the transfer comb. Large numbers of transfer combs may be employed in practice of standard dimensions so that, not only may the same comb be repeatedly applied to the winding machine, with assurance that the teeth will exactly aline with the reed pins, or to the tubing machine with assurance that the teeth will exactly aline with the needles and tubes, but successive standard combs may be used in each machine with certainty that the yarns held by one clamp will bear exactly the same relation to the reed pins, needles and tubes as the yarns held by another clamp where the same pattern has been used in each case. This not only provides effectually for the transference of the yarn strands from one machine to the other and for the tubing of the yarns with the minimum chances of disarrangement in the intended pattern, but by the use of a single standard instrument of transference which relates the yarns as seized by the needles to the yarns as separated by the reed pins, great rapidity of operation is secured with a minimum of attention on the part of the operator. The provision also for the effectual guidance of the needle both in entering and emerging from opposite ends of the tubes practically enforces and insures the drawing in every instance of the intended pattern.

It is to be understood that the guiding devices for the needles between the yarns and the tubes not only act to correct faulty alinement of the needles due to disarrangement of the tubes as mentioned, but also forcibly

to guide and direct the needles while advancing and passing through the yarn, as well as to hold them positively fixed in position during the shifting of the transfer comb. It is to be understood that these three functions or any of them may be performed by separate instrumentalities or by the same instrumentality, and that our invention, in its broad aspects, is not necessarily limited to a machine where guiding devices are employed performing all three functions specified.

While we have herein shown and described one specific form of our invention for purposes of illustration, it is to be understood that the same is not limited to the details of construction, nor to the specific arrangement of parts herein shown, but that extensive deviations may be made from the illustrated embodiment without departing from the spirit thereof.

Having thus described our invention, what we claim is:

1. The combination with an alining guide for holding separated and in proper order the free ends of the tuft yarns in carpet manufacture, said guide having a series of teeth with intervening spaces to receive the yarns and having also means to close the spaces to prevent exit of the yarns, of a spool, and means for attaching the guide to the spool.

2. The combination with a spool for carrying tuft yarns in carpet manufacture of an alining guide for holding the free ends of the yarns separated and in proper order, said guide having a series of teeth with intervening spaces to receive the yarns and having also means to close the spaces to prevent exit of the yarns, and means carried by the guide for removably attaching the same to the spool.

3. The combination with a spool for carrying tuft yarns in carpet manufacture of an alining guide for holding the yarns separated and in proper order while still permitting longitudinal draft thereof, and means for removably fastening said guide to said spool and maintaining the same pressed against the wound on yarns to prevent the unwinding thereof.

4. The combination with a spool for carrying tuft yarns in carpet manufacture, of a comb for holding the yarn ends separated and in proper order, and a resilient attachment device at each end of the comb for securing the same to the ends of the spool.

5. The combination with the spool 5, of the transfer comb 1, the retainer 18, and the attachment device 20 for the comb.

6. In a tubing machine, the combination with a removable transfer means for holding the free ends of the tuft yarns unclamped and subject to free longitudinal draft but separated and in proper order, said transfer means being adapted to be applied to the

- 5   yarns at the spooling machine and to be transferred with the wound-on yarns on the spool to the tubing machine, of means for holding a tube frame on the tubing machine, means also for holding thereon the transfer means in predetermined relation to the tubes to align the yarns with reference thereto, and tubing means for engaging the yarns while held in said transfer means and placing them through the tubes.
- 10   7. In a tubing machine, the combination with a removable transfer comb for holding the free ends of tuft yarns unclamped and subject to free longitudinal draft but separated and in proper order, said transfer comb being provided with means obstructing the spaces between the teeth thereof to prevent exit of the yarn while still permitting the longitudinal draft thereof, and said transfer comb being adapted to be applied to the yarns at the spooling machine and to be transferred with the wound-on yarns on the spool to the tubing machine, of means for holding a tube frame on the tubing machine, means for holding the transfer comb in predetermined relation to the tubes of the tube frame to align the yarns with reference thereto, and tubing means for engaging the yarns while held in said transfer comb and placing them through the tubes.
- 15   8. In a tubing machine, the combination with a removable transfer means for holding the free ends of the tuft yarns unclamped and subject to free longitudinal draft but separated and in proper order, said transfer means being adapted to be applied to the yarns at the spooling machine and to be transferred with the wound-on yarns on the spool to the tubing machine, of means for holding a tube frame on the tubing machine, means also for holding thereon the transfer means in predetermined relation to the tubes to align the yarns with reference thereto, a series of threading devices and means for causing them simultaneously to engage the yarns while held in said transfer means and place them simultaneously through the tubes.
- 20   9. The combination with spooling mechanism, a yarn alining guide arranged between the spool and the bobbin, means for directing the yarns thereover, and means for elevating the guide to receive the yarns, said guide being removable with the spool to maintain the yarns separated and in proper order.
- 25   10. In a tubing machine, the combination with a removable transfer guide transferable from the spooling machine with the wound-on yarns for holding unclamped but separated and in proper order the free ends of tuft yarns in carpet manufacture, of means for holding a tube frame and means for threading said yarns through the tubes of a tube frame.
- 30   11. The combination with a spooling machine, of an alining guide to hold separated and in proper order the tuft yarns, and a holder for said guide between the spool and the bobbins movable toward the yarns to engage the guide with the same.
- 35   12. The combination with a spooling machine, of a transfer comb, a holder between the spool and the bobbins, and means for raising the holder relatively to the yarns.
- 40   13. The combination with a spool for holding tuft yarns in carpet manufacture, of an alining guide to hold the free ends of said yarns, said guide being transferable with said spool, a threading machine to which said guide and spool are both applicable, threading needles, and means for shifting said guide in said threading machine to lay the yarns across the needles.
- 45   14. In a tubing machine for tuft yarns, the combination with means for holding the tubes, a plurality of needles, a spool, an alining guide transferable with the spool, and a shifting holder for the alining guide.
- 50   15. In a tubing machine for tubing tuft yarns for carpet manufacture, the combination with means for holding the yarns, of means to receive the tubes, and a holding member shaped to conform to the tubes and applicable thereto after their insertion in the machine.
- 55   16. In a machine for tubing tuft yarns for carpet manufacture, the combination with means for receiving the tubes, of a notched or toothed holding clamp, and means for moving said clamp into engagement with the tubes after their installation in the machine.
- 60   17. In a machine for tubing tuft yarns for carpet manufacture, the combination with tube frame-receiving means, of means adapted to enter between the tubes and hold the same positioned after their installation in the machine.
- 65   18. In a machine for tubing tuft yarns for carpet manufacture, the combination with needles, of means to receive a tube frame, a toothed bar mounted for swinging movement, and means for swinging said bar to cause its teeth to enter between the adjacent tubes and clamp the same in alinement with the needles.
- 70   19. In a machine for tubing tuft yarns for carpet manufacture, the combination with a flat tube receiving member, of movable holding means having an irregular surface shaped with reference to the shape of the tubes adapted to be applied to the tubes after installation in the machine and hold the same in position against said receiving member.
- 75   20. In a machine for tubing tuft yarns for carpet manufacture, the combination with needles, of means to receive a tube frame, and movable means applicable after installation in the machine.

- the installation of the tubes in the machine to enforce an alining adjustment of the tubes with relation to the needles.
21. In a machine for tubing tuft yarns for carpet manufacture, the combination with needles, of means to receive a tube frame, and movable means to wedge the tubes laterally into alinement with the needles after installation in the machine.
22. In a machine for tubing tuft yarns for carpet manufacture, the combination with yarn drawing means, of spool holding means, and means to hold the spool against unwinding due to the draft on the yarn while permitting the operator to release and unwind the spool in the holder for adjusting the yarn, the release of the spool being dependent on pressure thereagainst.
23. In a machine for tubing tuft yarns for carpet manufacture, the combination with spool holding means, of locking means, and means for yieldably pressing the spool into engagement with the said locking means.
24. In a machine for tubing tuft yarns for carpet manufacture, the combination with spool holders, of a spool locking member for said holders, and means for simultaneously applying or releasing said holding members.
25. In a machine for tubing tuft yarns for carpet manufacture, the combination with a pair of spool holders, of a toothed locking dog pivoted on each holder to engage the heads of the spool, yielding means for pressing said spool heads into engagement with said dogs, said spool being movable against said means to release the same therefrom, and an operating member connecting said dogs to cause their simultaneous application or release.
26. In a machine for tubing tuft yarns for carpet manufacture, the combination with means for holding the yarns separated and in proper order for engagement with the tubing devices, of means for shifting said yarn-holding means comprising a reciprocating operating member, and a shifting member operated thereby, and means to effect lost motion between said operating member and shifting member.
27. In a machine for threading tuft yarns through the tubes of a tube frame for carpet manufacture, the combination with means for holding the tubes, a plurality of needles, means to advance the latter to enter the tubes, and separating and guiding means for holding the needles in predetermined and separated relation, said separating and guiding means being adapted to advance with the needles.
28. In a machine for threading tuft yarns through the tubes of a tube frame, the combination with means for holding the tubes, a plurality of needles, means for advancing and retracting the latter relatively to the tubes, and separating and guiding means for holding the needles in predetermined and separated relation, said separating and guiding means being adapted to retract with the needles.
29. In a machine for threading tuft yarns through the tubes of a tube frame, the combination with means for holding the tubes, a plurality of needles, means for advancing and retracting the latter relatively to the tubes, and guiding means for the needles adapted to hold separated and alined the forward ends of the needles when retracted, but to advance with the needles to a position adjacent the tubes as the needles pass through the same.
30. In a machine for threading tuft yarns through the tubes of a tube frame, the combination with means for holding the tubes, a plurality of needles, means for advancing and retracting the latter relatively to the tubes, a guiding member with which said needles are slidably engaged, a yieldable connection to advance said guiding member with said needles, an abutment to position said guiding member adjacent the tubes, and means to withdraw said guiding member with the needles on the retraction of the latter.
31. In a machine for threading tuft yarns, the combination with tube holding means, a plurality of needles, means for passing them through the tubes, and means for positively engaging and guiding the needles where they emerge from the tubes.
32. In a machine for threading tuft yarns, the combination with tube holding means, a plurality of needles, means for passing them through the tubes, means for holding the yarns, and guiding means for positively engaging the needles between the yarns and tubes when the needles seize the yarns.
33. In a machine for threading tuft yarns, the combination with tube holding means, a plurality of needles, means for passing them through the tubes, and laterally fixed guiding means for the needles where they emerge from the tubes.
34. In a machine for threading tuft yarns, the combination with tube holding means, a plurality of needles, means for passing them through the tubes, and movable guiding means to engage the needles as they emerge from the tubes and force the same into the required alinement.
35. In a machine for threading tuft yarns, the combination with tube holding means, of a plurality of needles, means to advance the needles through the tubes, yarn holding means, movable guiding means for the needles between the tubes and the yarns, and means connected with the needle advancing means for moving said guiding means to engage with the needles.
36. In a machine for threading tuft yarns,

- the combination with tube holding means, of a plurality of needles, means to advance the needles through the tubes, yarn holding means, a toothed or notched guide bar, and means for swinging the same with its teeth between the ends of the needles as the latter emerge from the tubes. 44. In a machine for threading tuft yarns in carpet manufacture, the combination with means for holding the tubes, means for threading the yarns therethrough, and means for holding clamped the free ends of the 70 drawn in yarn strands.
37. In a machine for threading tuft yarns, the combination with a plurality of needles, 10 of tube holding means, yarn holding means, movable needle guiding means between the yarns and the tubes, and means for automatically applying and withdrawing the same. 45. In a machine for threading tuft yarns in carpet manufacture, the combination with threading means, means for supporting the tubes, means for holding the yarns, and 75 means for holding clamped after the drawing-in operation both the free ends of the drawn in yarns and the tube frame.
38. In a machine for threading tuft yarns, 15 the combination with tube holding means, of a plurality of needles, a needle holder, a clamping member, and means for retaining the needles in the holder comprising a transverse key member seated partly in the needle 80 and partly in the clamping member.
39. In a machine for placing tuft yarns in carpet manufacture through the tubes of a tube frame, the combination with means for holding the tube frame of a thread-placing device, means for projecting the needle 85 through a tube from one end thereof to the other to tube a yarn strand, guiding means for the thread-placing device adapted to advance toward the tube with the same, and additional guiding means adapted to engage 90 with the thread-placing device after emerging from the opposite side of the tube to enforce appropriate alinement. 46. In a machine for threading tuft yarns in carpet manufacture, the combination with a support for the tube frame of a plurality of needles, means to advance the needles 95 through the tubes, needle guiding means for advancing and retracting with the same, and yarn trimming means adapted to engage the drawn-in yarns between the needles and the tubes after the retraction of the guiding means. 47. In a machine for threading tuft yarns in carpet manufacture, the combination with means for supporting the tubes, a plurality of needles for simultaneously threading the yarns therethrough, operating devices for moving said needles, and a yarn holder also connected with said operating devices and adapted to be applied to the ends of the drawn-in yarn strands after the threading operation. 48. In a machine for threading tuft yarns in carpet manufacture, the combination with tube holding means, a plurality of drawing-in needles, one for each tube, yarn holding means, operating means to advance the needles and draw the yarns simultaneously through the tubes, a yieldably mounted holding member connected with said operating means and adapted to be applied to the ends of the drawn in yarn strands, and means for withdrawing said holding member from the yarn strands independently of the movement of said operating means. 100
40. In a machine for threading tuft yarns in carpet manufacture, the combination with 105 a support for the tube frame of a plurality of needles, means to advance the needles through the tubes, needle guiding means for advancing and retracting with the same, and yarn trimming means adapted to engage the drawn-in yarns between the needles and the tubes after the retraction of the guiding means. 49. In a machine for placing tuft yarns in carpet manufacture through the tubes of a tube frame, the combination with means for holding the tube frame, of means for holding the yarns, a thread-placing device, means for projecting said device through a tube of the tube frame from one end thereof 110 for the purpose of tubing a yarn strand and guiding means for engaging the thread-placing device after emergence from the opposite end of the tube to enforce appropriate alinement of said device. 50. In a machine for placing tuft yarns in carpet manufacture through the tubes of a tube frame, the combination with a series of needles to place the tuft yarns simultaneously through the tubes by a relative movement between the tubes and the bank of needles, of guiding means for engaging with the ends of the needles after they emerge 115 from the tubes to enforce alinement with the yarns. 120
41. In a machine for threading tuft yarns in carpet manufacture, the combination with 125 threading means, means to trim the yarn ends when threaded, and means for holding clamped the drawn-in yarn ends during the trimming operation. 42. In a machine for threading tuft yarns in carpet manufacture, the combination with tube holding means, threading means, trimming means for trimming the ends of the drawn-in yarns, and means for holding 130 clamped the yarn strands between the trimming means and the tubes. 43. In a machine for threading tuft yarns in carpet manufacture, the combination with threading means, of trimming means for trimming the ends of the drawn in yarns comprising a movable knife adapted to be forced against the yarns, and a yarn holder movable to engage the latter prior to the engagement therewith by the trimming member. 135

51. In a machine for threading tuft yarns through the tubes of a tube frame for use in carpet or like looms the combination with a series or bank of needles that simultaneously draw the tuft yarns through the tubes by a relative movement between the tubes and the needles of a separating and guiding device for holding the needles in a predetermined separated relation whereby the latter are aligned and constrained to move in a fixed path relatively to the tubes, said guiding device being movable relatively to the needles and to the tubes.
52. In a machine for threading tuft yarns through the tubes of a tube frame for use in carpet and like looms the combination with a series or bank of needles that simultaneously draw the tuft yarns through the tubes by a relative movement between the tubes and the needles of a separating and guiding device for holding the needles in a predetermined separated relation, said guiding device being arranged to advance with the needles.
53. In a machine for threading tuft yarns through the tubes of a tube frame for use in carpet and like looms the combination with a series or bank of needles that simultaneously draw the tuft yarns through the tubes by a relative movement between the tubes and the needles of a separating and guiding device for holding the needles in a predetermined separated relation, said guiding device being arranged to advance with the needles until the latter enter the tubes when the guiding device is brought to rest while the needles continue their movement through the tubes, said guiding device being also arranged to return with the needles to the normal position.
54. A machine for placing tuft yarns in carpet manufacture through the tubes and a tube frame having a series or bank of needles, guiding means for the needles adapted to advance toward the tubes with the needles, and means also for guiding the needles adapted to engage with the needles after their emergence from the opposite ends of the tubes.
55. In a machine for threading tuft yarns through the tubes of a tube frame for use in carpet manufacture, the combination with a series or bank of needles, means for causing relative movement between the tubes and the series for causing the needles to place the tuft yarns through the tubes, a guiding device for engaging the ends of the needles to guide them after they emerge from the opposite ends of the tubes, and means operated by the moving mechanism for bringing said guiding device into engagement with the needles.
56. In a machine for threading tuft yarns through the tubes of a tube frame for use in carpet manufacture, the combination with
- a series or bank of needles, means for causing relative movement between the tubes and the series for causing the needles to place the tuft yarns through the tubes, a guiding device for the needles comprising a movable toothed bar, the teeth of which are arranged to enter between the needles on their emergence from the tubes, and means operated by the needle advancing mechanism for bringing the teeth of the bar into engagement with the needles.
57. In a machine for threading tuft yarns through the tubes of a tube frame having a series of guide tubes to be threaded, means for holding a series of yarns, a series or bank of needles facing the bank of tubes, there being provided a needle for each tube to be threaded, means for moving the needles simultaneously with relation to the tubes to simultaneously thread the latter, and a rigid slotted guiding member extending transversely the bank of needles and guiding and holding separated the needles in the slots thereof, said guiding member being arranged to advance with the needles in relation to the tubes until the latter are entered by the needles, then to be brought to rest with relation to the tubes while the needles are positioned through the tubes, said guiding member being also arranged to return with the needles to their normal position.
58. In a machine for threading tuft yarns through the tubes of a tube frame for carpet manufacture, the combination with means for holding a tube frame having a series of guide tubes to be threaded, means for holding a series of yarns, a series of thread placing devices arranged in operative relation to the tubes, there being provided a thread placing device for each tube to be threaded, means to advance and retract the thread placing devices relatively to the tubes, each in alignment with its respective tube, and guiding means for the thread placing devices adapted to hold separated and aligned the forward ends of the thread placing devices when retracted but to advance with the latter to a fixed position adjacent the tubes as the thread placing devices pass through the same.
59. In a machine for threading tuft yarns through the tubes of a tube frame for carpet manufacture, the combination with means for holding a tube frame having a series of guide tubes to be threaded, means for holding a series of yarns, a series of thread placing devices arranged in operative relation to the tubes, there being provided a thread placing device for each tube to be threaded, and the series of thread placing devices facing the tubes each aligned with its respective tube, means to cause relative movement between the tubes and the

- thread placing devices to cause the latter to enter the tubes, and rigid guiding means extending transversely the thread placing devices and guiding and holding separated 5 the latter during their thread placing movement, said guiding means being adapted to advance with the needles relatively to the tubes but being movable relatively to the thread placing devices.
- 10 60. In a tubing machine the combination with transfer means for holding the free ends of tuft yarns in carpet manufacture comprising a toothed sheet metal holding strip and a U-shaped retaining strip adapted 15 to be applied to said holding strip to close the open spaces of the teeth thereof, said strip being of lesser width than the depth of the teeth whereby the yarns are held therein unclamped and subject to free longitudinal draft but separated and in proper order, said transfer means being adapted to be applied to the yarns in the spooling machine and to be transferred with the wound-on yarns on the spool to the tubing 20 machine, of means for holding the tube frame on the tubing machine, means also for holding thereon the transfer means in predetermined relation to the tubes to align the yarns with reference thereto, and tubing 25 means for engaging the yarns while held in said transfer means and by said retaining strip and placing them through the tubes.
- 30 61. In a tubing machine the combination with a removable transfer comb for holding the free ends of tuft yarns unclamped and subject to free longitudinal draft but separated and in proper order, said transfer comb being provided with means obstructing 35 the spaces between the teeth thereof to prevent exit of the yarns while still permitting the longitudinal draft thereof and said transfer comb being adapted to be applied to the yarns at the spooling machine 40 and to be transferred with the wound-on yarns on the spool to the tubing machine, means for holding a tube frame on the tubing machine, means for holding the transfer comb in predetermined relation to the tubes 45 of the tube frame to align the yarns with reference thereto, and tubing means for engaging the yarns while held in said transfer comb and with said obstructing means applied thereto and placing them through the 50 tubes.
- 55 62. In a tubing machine the combination with removable transfer means for holding the free ends of tuft yarns unclamped and subject to free longitudinal draft but separated and in proper order, said transfer 60 means being adapted to be applied to the yarns at the spooling machine and to be transferred with the wound-on yarns on the spool to the tubing machine, of means for holding a tube frame on the tubing machine, means for also holding thereon the transfer means in predetermined relation to the tubes to align the yarns with reference thereto, tubing means for engaging the 65 yarns while held in said transfer means and placing them through the tubes, and means for causing relative movement between said transfer means and said tubing means laterally with relation to said tubing means for assisting the engagement of the yarns by the 70 latter.
- 75 63. In a tubing machine the combination with a removable transfer comb for holding the free ends of tuft yarns unclamped and subject to free longitudinal draft but separated and in proper order, the said comb being adapted to be applied to the yarns at the spooling machine and to be transferred with the wound-on yarns on the spool to the tubing machine, of means for holding a tube 80 frame on the tubing machine, means for holding the transfer comb thereon, a series of thread placing devices, means for causing relative movement between the comb and the thread placing devices laterally with relation to the thread placing devices to engage the latter with the yarns, and means for causing relative movement between the tubes and the thread placing devices to thread the 85 yarns through the tubes.
- 90 64. The combination with a transfer comb adapted to be applied to tuft yarns at the spooling machine and to be transferred with the wound-on yarns on the spool to the tubing machine of means for holding a tube 95 frame on the tubing machine, means for holding the comb on the tubing machine, a series or bank of needles, means for shifting the comb on the tubing machine with relation to the needles, and means for moving the needles through the tubes.
- In testimony whereof, we have signed our names to this specification, in the presence of two subscribing witnesses:
- EDGAR F. HATHAWAY,
CHARLES LEA.
- Witnesses:
EVERETT S. EMERY,
ROBERT H. KAMMLER.
